SNAP FIT INTERLOCKING CHECKER

Willard S. Peterson, Astoria, N. Y.

Application December 3, 1946, Serial No. 713,674

4 Claims. (Cl. 273—137)

1

This invention relates to improvements in game pieces, and more particularly to an improved checker for use in the game of checkers or draughts, or any other games requiring similar movable game pieces.

In the game of checkers, each player is provided with a required number of pieces which are moved from square to square on a checker board. At the beginning of the game each piece may be moved only in one general direction until it reaches the furthermost squares, which are known as "the king row." When the piece reaches the king row, it becomes a king, and its playing or game value is enhanced so that it may thereafter during the game be moved in any direction. In order to distinguish the king from other pieces, the king is formed by placing one checker upon another, and then both checkers are thereafter moved together as a single game piece or king.

It is necessary at all times during the game to know in which square a given checker piece is located. However, if the game or checker board is inadvertently jarred, tilted, or otherwise disturbed, the two checker pieces which form the king become displaced, and may fall in different playing squares. In this event, it is difficult to determine in which playing square the king was located prior to the mishap. Difficulty is also frequently encountered when the player attempts to "jump" a king over another game piece, because during the jumping operation the top checker often falls from the lower checker onto the playing area, thereby disrupting the playing relation of other checkers.

After the games are completed, the checkers are usually compactly stored in a container or checker box with a number of the checkers disposed in superposed relation.

Therefore, it is an object of this invention to provide an improved locking checker piece which is constructed and arranged so that the inherent resiliency or ready deformability of the material forming the checker piece is utilized to lock two or more checkers together.

Another object of this invention is to provide improved checker pieces in which the ready deformability of the material forming the base is utilized to secure two or more pieces together, the locking instrumentalities being constructed and arranged so that the locking action is effected by a very slight manual effort.

A specific object of the invention is to provide improved checker pieces which are formed of material having a degree of resiliency and each piece having spaced locking members which are constrained to locking position by the resiliency of the material forming the checkers.

2

A more specific object of this invention is to provide improved checker pieces, each formed of resilient material and having a reduced projecting portion and a recessed portion, one of the portions being provided with a locking groove and the other portion provided with spaced locking projections which are permitted by the resiliency of the material forming the checker to yield sufficiently to engage and disengage the locking groove of a second piece to lock the two pieces together or to permit their convenient separation.

It is also an object of this invention to provide a checker mechanism of generally improved construction and arrangement, whereby the device will be simple, durable, and inexpensive, as well as convenient, practical, serviceable, and efficient in its use.

With the foregoing and other objects in view 20 which will appear as the description proceeds, the invention resides in the combination and arrangement of parts, and in the details of construction hereafter described and claimed, it being understood that various changes in form, proportion and minor details of construction may be made within the scope of the claims without departing from the spirit or sacrificing any advantages of the invention.

For a complete disclosure of the invention, a 30 detailed description thereof will now be given in connection with the accompanying drawings forming a part of the specification, wherein:

Figure 1 is a side elevation of the improved checker;

Figure 2 is a top plan view of the checker;

Figure 3 is a bottom plan view of the checker;

Figure 4 is a transverse sectional view depicting two checkers in interlocked relation;

Figure 5 is a side elevation of a modified form of checker; and

Figure 6 is a transverse sectional view of a modified form of the invention, depicting two checkers in interlocking relation.

Referring to the drawings, in which similar 45 reference characters designate corresponding parts, 10 indicates the cylindrical body of the improved checker, and this body has a lower recess portion 11 and an upper projecting portion 12. The projecting portion 12 is reduced in diameter and its outer surface is preferably frusto-conical in configuration. The inclined conical surface 13 of the projecting portion 12 serves as a guide surface, as will be hereinafter explained. A circular locking groove 15 is formed 50 at the intersection of a flat top surface 16 of the checker body 10 and lower portion of the frusto-conical guide surface 13, for a purpose to be hereinafter explained.

The lower portion 11 of the checker body 10 is provided with a recess 17 adapted to snugly receive the projecting portion 12 of a similar checker, as will be more fully explained hereinafter. A number of locking projections or lugs 18 extend into the recess 17 from the lower annular wall 20 which surrounds the recess 17.

When it is desired to secure two checkers together to form a "king," one checker is positioned over another, with the recess 17 of the top checker in alignment with the projecting portion 12 of the lower checker. When the upper checker is placed on the lower checker, the locking projections 18 engage the upper portion of the frusto-conical guide surface 13, and then a slight downward pressure forces the projections 18 downwardly along this guide surface until the projections snap into the locking groove 15, thereby securely locking the two checkers together in position to form a king piece. As the locking projections are forced downwardly along the frusto-conical guide surface 13, the resilient annular wall 20, surrounding the recess 17, permits the locking lugs to yield outwardly sufficiently to pass over the enlarged lower terminal of the guide surface 13. As the locking lugs 18 move outwardly, the segment of the annular wall 20 defined between two adjacent locking lugs, is distorted from its circular configuration inwardly towards a cord passing through the engaging portions of the adjacent locking lugs. This yielding or stretching movement of the annular wall 20 of the recessed portion of the checker permits the lugs to move sufficiently to snap to and from engagement with the locking groove 15.

When it is desired to separate the checkers, the upper checker is moved axially away from the lower checker, thus causing the locking projections 18 to snap from engagement with the locking groove 15.

In the form of the invention depicted in Figure 5, the annular wall 20a surrounding the recess is provided with spaced slits, preferably formed at each side of a locking projection 18a. By this arrangement, the portion of the wall 20a which carries a locking projection 18a, yields outwardly independently of the remainder of the wall when the checkers are moved to and from locking engagement with each other.

Figure 6 depicts a form of the invention having a locking groove 15b formed in the inner surface of the annular wall 20b surrounding the recess 17b, for the reception of locking projections or lugs 18b which extend outwardly from the projecting portion 12b of each checker, when the checkers are disposed in locking relation. The recess 17b is defined by tapered or frusto-conical walls 13b which serve as guide surfaces for sliding engagement by the locking projections 18b when the checkers are being pressed into locking engagement. In this arrangement the resilient annular wall 20b yields sufficiently to permit the lugs to ride up the inclined guide surface 13b to snapping engagement with the locking groove 15b. If desired, the annular wall 20b may be provided with slots or slits similar to those disclosed in Figure 5 to permit portions of the wall to yield independently of other portions.

After the games have been completed, the checkers are usually stored in a suitable container or checker box where a number of checkers are disposed in superposed relation. If the depth of the container is sufficient to accom-

modate three or more checkers in superposed relation, then this number of checkers are locked together in axial alignment and placed in the container in this condition, thus facilitating the packing operation in storing the checkers for future use.

I claim:

1. In a checker member, a relatively thin and flat body formed of readily deformable material and having its lower face provided with a recess, a projection integral with said body rising from the upper face thereof, said projection corresponding substantially with the size and shape of said recess, the side wall of said projection having a locking groove therein, and a locking rib integral with said body and extending into the side wall of said recess.

2. A checker member comprising a relatively thin flat body formed of readily deformable material and having its lower face provided with a recess, a locking rib in the side wall of said recess projecting into the latter, a projection rising from the upper face of said body of substantially the same shape and size of said recess, and said projection having a locking groove in its side wall corresponding to the size and shape of said locking rib.

3. A checker member comprising a relatively thin flat body formed of readily deformable material and having a circular recess opening inwardly from its lower face, a locking rib in the side wall of said recess and projecting into the latter, an annular projection rising from the upper face of said body corresponding in shape and size with said recess, and the side wall of said projection having a locking groove corresponding in size, shape and location with the locking rib of said recess wall.

4. A checker member comprising a relatively thin flat body formed of readily deformable material and having a circular recess opening inwardly from its lower face, the side walls of said recess inclining inwardly in the direction of the top of said body, a locking rib on said side wall projecting into said recess, an annular projection rising from the upper face of said body corresponding in shape and size with said bottom recess, the side walls of said projection corresponding to the angularity of the side walls of said recess, and said projection side wall having a locking groove therein corresponding to the size, shape and location of the rib of said recess wall.
